Specification for Design.

Patented Nov. 22, 1921.

Application filed June 26, 1920. Serial No. 392,101. Term of patent 14 years.

To all whom it may concern:

Be it known that I, FREDERICK G. GRUEN, a citizen of the United States of America, and a resident of Cincinnati, in the county of Hamilton and State of Ohio, have invented an original and ornamental Design for a Wrist-Watch, of which the following is a specification, reference being had to the accompanying drawing, forming a part thereof.

The figure is a perspective view of a wrist-watch showing my new design.

I claim:

The ornamental design for a wrist-watch as shown.

FREDERICK G. GRUEN.
